UNITED STATES PATENT OFFICE.

CHARLES M. NEISS, OF NEWARK, NEW JERSEY.

TENT.

1,276,255.

Specification of Letters Patent. Patented Aug. 20, 1918.

Application filed December 29, 1917. Serial No. 209,546.

To all whom it may concern:

Be it known that I, CHARLES M. NEISS, a citizen of the United States, residing at Newark, in the county of Essex and State 5 of New Jersey, have invented new and useful Improvements in Tents, of which the following is a specification.

This invention relates to a tent of the shelter type which is principally intended for 10 army use, although the construction of the tent is such that it may be advantageously employed for camping and other purposes if desired.

The primary object of the invention is to 15 provide an inexpensive and durable tent of this character having a frame embodying a construction whereby the tent may not only be quickly set up or taken down but when not in use may be made into a compact 20 bundle for transportation purposes.

Another object of the invention is to provide the tent with a frame wherein the poles and fly supports comprising the frame are 25 of the sectional type to permit the sections comprising these members to be nested when the tent is not in use.

Another object of the invention is to so construct the fly supports and tent poles that the sections of the fly supports may be held 30 assembled by the poles when the tent is in use.

A further object of the invention is to provide the frame of the tent with couplings, the construction of which are such 35 that the couplings may not only be employed to connect the sections comprising the end poles of the tent, but may be used as a support for a hammock of novel construction for connection therewith.

40 A still further object of the invention is to provide the tent with a fly, the shape of which is such as to insure the ventilation of the tent under all conditions.

With these and other objects in view, the 45 invention resides in the novel combination and arrangement of parts which will be hereinafter described and particularly pointed out in the claims.

In the drawings:

50 Figure 1 is a sectional view through a tent constructed in accordance with the invention.

Fig. 2 is a vertical transverse section through Fig. 1.

55 Fig. 3 is an enlarged sectional view

through the nested pole sections which may be employed to form a part of the tent.

Fig. 4 is an enlarged sectional view 60 through one of the tent poles and the fly support associated therewith.

Fig. 5 is a perspective view of a portion of the ridge pole of the tent and the fly support used in connection therewith.

Fig. 6 is a view of the sections which may be employed to form the fly supports of the 65 tent.

Fig. 7 is a detail perspective view of a portion of one of the fly supports.

Fig. 8 is a similar view showing the 70 slightly modified form of fly support.

Fig. 9 is a detail sectional view through one of the tent pole couplings and a portion of the hammock supported thereby.

Fig. 10 is a similar view through another 75 of the tent pole couplings.

Fig. 11 is a sectional view on the line 11—11 of Fig. 9.

Like characters of reference denote the 80 corresponding parts throughout the several views in the drawings.

Referring now to the drawings in detail the letter A designates a tent of the shelter type which is primarily intended for army use. The tent A when constructed in accordance with the invention comprises a 85 frame B which serves as a support for a fly C.

The frame B includes a pair of end poles 15 and a ridge pole 16 with which and the end poles are detachably connected supports 90 17 for the fly C.

Each end pole 15 comprises a tubular lower pole section 18 and a tubular upper pole section 19 of less diameter than the inside diameter of the lower pole section and 95 detachably connected therewith by a coupling 20. Detachably connected with the pole section 18 at its lower end is a collar 21 at one end of which is a circumferentially extending flange 22 provided with suitable 100 openings to permit the pole section to be secured to the ground with pegs or the like, as shown in Fig. 1 in the drawings. The upper pole section 19 is interiorly threaded for a portion of its length adjacent its upper 105 end and has formed therein below said threaded portion a threaded opening 23. The coupling 20 is threadededly engaged with the pole sections 18 and 19 and is provided upon opposite sides with tubular arms 24 in 110

each of which is a longitudinally extending slot 25. Each arm 24 has formed thereon adjacent its outer end a tubular extension 26 which opens out into the arm and is arranged within a sleeve 27 on the arm. Detachably connected with the collar 21 between the arms 24 is a tube 28 in opposite sides of which are formed openings in line with the slots 25.

10 The ridge pole 16 comprises a pair of tubular pole sections 29 and 30 which are connected by a coupling 31 threadedly engaged with the pole sections and having formed in one side thereof an opening which 15 is in line with a threaded extension 32 on the coupling. The pole sections 29 and 30 are threaded for a portion of their length adjacent their outer ends and these threaded portions extend within the threaded 20 openings in the pole sections 19.

By constructing the poles comprising a part of the frame as above described, the pole sections 19 may be arranged within the pole sections 18 when the tent has been taken 25 down and a pole section of the ridge pole may be arranged within each of the pole sections 19 as shown in Fig. 3 in the drawing, thus allowing the pole portion of the tent frame to be arranged in compact form for 30 transportation.

The fly supports 17 which are preferably 3 in number are each formed from a pair of fly support sections 33 and 34 with the sections comprising the fly supports at the ends 35 of the tent frame held assembled by the pole sections 19, while the sections which comprise the central fly support are held assembled by the extension 32 on the coupling 31. Each of the fly support sections 33 and 40 34 includes a curved loop 35, the free ends of which are embedded in the head of a threaded stem section 36 and these stem sections when the sections 33 and 34 are assembled, provide the fly support with a stem 45 which may be arranged within one of the pole sections 19 or within the extension 32 on the coupling 31. The stem sections 36 are recessed to provide the stem with a socket into which an end of the pole section 50 29 or 30 is adapted to extend to lock the support sections in the holder in which they are mounted. One of the stem sections 36 in each fly support is provided with a tongue 37 which when arranged within the 55 other stem section on the support holds said stem sections in alinement with each other.

The fly C which overlies the frame B has a curved top and oppositely inclined sides 38 which are connected by walls 39 closing 60 the ends of the tent. Both the side and end walls of the fly are provided in their lower edges with semicircular shaped recesses 40 which not only insure proper ventilation of the tent but affords a means of entrance 65 thereto. The lower edge of the fly C is

provided with rings 41 which are connected to ropes 42 for engagement with the tent pegs by means of which the fly may be retained on the frame B.

Extending longitudinally of the tent A is 70 a hammock 43 at one end of which is a rod 44 which is arranged within a slotted holder 45. The holder 45 and rod 44 are arranged within a casing 46 which is provided with a longitudinally extending slot 47 through 75 which the hammock 43 is passed. The casing 46 has formed thereon extensions 48 which open out into the casing and are arranged within sleeves 49.

The casing 46 is attached to one of the 80 couplings 20 by a cable 50 which extends exteriorly of the casing through the extensions 48 and is threaded through the extensions and arms on the coupling with which the casing is to be connected. The cable 50 is 85 passed through coiled expansion springs 51 into which extends the extensions 48 on the casing and the extensions on the arms of the coupling with which the cable is to be engaged.

The ends of the cable 50 are passed 90 through the slots 25 in the arms on the coupling and through the openings in the tube 28. The cable 50 terminates at one end in a loop through which is passed a snap ring 52, connected with the other end of the cable and engaged with a guy rope 53.

The other end of the hammock may be connected with the coupling on the other end 100 pole of the tent frame in the manner above described if desired, although it is preferable that the said end of the hammock be connected with the above mentioned coupling by a cable 54 which is threaded through the arms on the coupling and through the tubular extension thereon and connected with a snap ring 55 connected with a guy rope 56.

From the foregoing description taken in connection with the accompanying drawings 110 it is apparent that a tent for army use has been provided which may be quickly set up and taken down and when not in use arranged in compact form for transportation.

Having thus described the invention what is claimed as new, is:

1. A tent comprising end poles each formed from an upper and a lower tubular pole section, a coupling connecting said pole sections, supporting arms on said couplings, ridge pole sections connected with the upper 120 end pole sections, a coupling connecting said ridge pole sections, fly supports mounted in the upper end pole sections and the last mentioned coupling; and a fly overlying and extending below said fly supports.

2. A tent comprising end poles each formed from a lower tubular pole section and an upper tubular pole section, each of said upper pole sections having a threaded opening adjacent its upper end, a coupling connect- 130

- ing the pole sections in each end pole, apertured supporting arms on said coupling, threaded ridge pole sections extending within said threaded openings, fly supports 5 having stems thereon extending within the upper pole sections engaged by the ridge pole sections, a coupling connecting said ridge pole sections, another fly support having a stem thereon passed through the coupling connecting said ridge pole sections and engaged by one of the ridge pole sections, and a fly on said fly supports.
3. In a tent, end poles each comprising a lower tubular pole section and an upper 15 tubular pole section detachably connected with the lower tubular pole section and adapted to be received therein when said pole sections are disconnected, detachably connected ridge pole sections connected with 20 said end poles adapted to be received in the upper sections thereof when said ridge and end pole sections are disconnected, curved fly supports mounted in said end and ridge poles, and a covering on said fly supports.
- 25 4. In a tent, tubular end poles having openings therein adjacent their upper ends, a pair of fly support sections above each end pole, mating stem sections on each pair of fly support sections extending within an end 30 pole and having an opening therein registering with the said opening in the end pole, ridge pole sections extending within the openings in the end poles and stem sections, a coupling connecting said ridge pole sec-
- tions having a transversely extending opening therein, and a pair of fly support sections having mating stem sections passed through the opening in said coupling, said last mentioned stem sections having an opening therein into which one of said ridge pole 40 sections extend.
5. In a tent, a fly support comprising a pair of stem sections, one of said sections having a groove therein, the other of said sections having a tongue to extend within 45 said groove, and a curved loop on each of said stem sections having its free end embedded in one end of the stem sections.
6. In a tent, spaced couplings, a pair of arms on each coupling having slots and 50 openings therein, a flexible strip between said couplings, a rod at one end of said strip, a holder in which said rod is mounted, a casing for said holder, coiled expansion 55 springs on said casing engaging the arms on the coupling adjacent thereof, a flexible element on said casing passed through the springs and through the arms on the coupling engaged by the springs, a guy rope connected with said flexible element, and a flexible element connected with the other end of 60 said strip and passed through the arms on the other of said couplings, and a second guy rope connected with the last mentioned flexible element exteriorly of the coupling. 65

In testimony whereof I affix my signature.

CHARLES M. NEISS.
